UNITED STATES PATENT OFFICE.

WILLIAM S. THOMAS, OF LINDEN, NEW JERSEY, ASSIGNOR TO THOMAS SPARK PLUG COMPANY, OF ROSELLE PARK, NEW JERSEY.

INSULATED ELECTRODE FOR SPARK PLUGS.

Application filed June 27, 1921. Serial No. 480,913.

To all whom it may concern:

Be it known that I, WILLIAM S. THOMAS, a citizen of the United States, residing at Linden, in the county of Union and State 5 of New Jersey, have invented certain new and useful Improvements in Insulated Electrodes for Spark Plugs, of which the following is a specification.

One object of my invention is to provide 10 an improved insulated electrode for spark plugs which will keep cooler while functioning in an internal combustion engine than insulated electrodes used prior to my present invention. This object I accomplish 15 by a novel construction which allows an open air space surrounding the positive electrode wire as far as possible toward the end or nose of the insulating core which enters the combustion chamber, thereby allowing a circulation of air at all times within 20 said insulating core and around said positive electrode wire.

Another object is to provide a structure 25 which will prevent the establishment of an excessive pressure even though any minor leak should be effected by or through the web of the insulating core.

It is a well known fact to those skilled 30 in the art that cement as generally applied in spark plugs has undesirable effect on the electrode structure and cannot be depended upon ordinarily to provide permanent joints and seals when subjected to the conditions imposed upon spark plugs.

Another and very important object of my 35 invention is to provide improved means of simple and durable construction for securing the electrode wire to the insulating core or shell; the same being rendered possible without the use of cement.

A further object is to provide in connection 40 with the insulating core or shell, a readily removable cap, the removal of which allows the connecting of the high tension lead to the electrode wires within the core and should the insulator be broken down above the shoulder or thickest portion of the insulating core, the spark will be visible and hence the structure does not require 45 the use of a delicate or technical appliance to determine whether the plug is in good working condition.

These objects, and other advantageous 50 ends which will be described hereinafter, I 55 attain in the following manner, reference

being had to the accompanying drawings in which

Figure 1 is an elevational view of an insulated electrode made in accordance with my present invention,

Figure 2 is an enlarged section taken on the line 2—2 of Figure 1,

Figure 3 is a bottom plan view of Figure 2, and

Figures 4 to 7 inclusive are enlarged fragmentary elevations showing slight modifications in the construction of the securing means of the electrode wire to the core or insulator shell.

Referring to the drawings, 8 represents an insulating core which may be made of any suitable electrode insulating material and includes a body portion 9 which is externally screw threaded at its upper end, as shown at 10, and a cap 11 which has internal screw threads 12 so that the cap can be screwed on the body portion 9; said cap including a chamber 13 positioned directly above the top of the body portion 9. This cap has radially disposed holes or 80 perforations 14 which communicate with the atmosphere and also with the chamber 13 permitting air to pass into and out of the chamber 13 as will be more fully described hereinafter. The body portion 9 has an enlarged external shoulder or flange 15 which is positioned above its lower end or nose 16. Furthermore the body portion 9 has a cylindrical cavity 17 extending axially and downward from the top surface 18 of 90 the body portion 9. This cavity terminates in a lower shoulder 19 and a counter cavity 20 of smaller diameter than the cavity 17 leads downwardly from the shoulder 19 and forms the top of a transversely extending 95 web 21; said web being formed integral with the other part of the core body 9. A recess or cavity 22 extends upwardly and axially from the bottom surface 23 of the insulator nose 16 and the upper wall of 100 this recess 22 provides the bottom of the web 21. An auxiliary insulating tube 24, preferably of mica, fits the cavity 17; the lower edge of the mica tube resting on the shoulder 19; the internal diameter of said 105 mica tube 24 preferably being larger than the diameter of the counter-cavity 20.

Referring particularly to Figure 2, an electrode wire 25 has a screw threaded portion which extends through a central hole 26 110

in the web 21 of the insulator; a part of this screw threaded portion of the electrode wire 25 extending upwardly into the space within the mica tube 24 and another part of this 5 screw threaded portion of the electrode wire extends below the web 21 and upon this latter part of the screw threaded portion of the electrode wire is screwed a small nut 27 which abuts the under surface of the web 21. 10 The diameter of the electrode wire 25 is small compared to the diameters of the counter cavity 20, recess 22 and internal diameter of the mica tube 24 so that there is a comparatively large air space existing between the 15 electrode wire and the inner surface of the mica tube 24. A second nut 28 is screwed on the upper portion of the electrode wire and abuts the top surface of the web 21 so that the web 21 is clamped between the nuts 20 27 and 28.

In assembling the parts, the nut 27 can be screwed downwardly on the threaded portion of the electrode before the electrode is inserted through the hole 26, after which 25 the upper portion of the electrode can be inserted upwardly through the hole 26 and a small nut-carrying wrench can be inserted downwardly through the tube 24 to apply the nut to the top end of the threaded portion of the electrode wire and the nut 28 can be screwed downwardly into firm clamping engagement with the top of the web 21; it being noted that sufficient space is provided between the sides of the nuts to permit 30 35 said small wrench to enter the space between the nut 28 and the side wall of the counter cavity 20.

The cap 11 has a metallic head 29 secured thereto and in the present instance I have 40 illustrated the head 29 including an enlarged flange 30, which abuts the uppermost surface of the chamber 13, and an angular portion 31 which may be embedded in the material of the cap so as to prevent rotation 45 between the head 29 and the cap. The head 29 includes an upwardly extending screw threaded stem 32 to which a thumb nut 33 is secured and I have also illustrated two other nuts 34 screwed on said stem and 50 between these nuts and the thumb nut the usual electric wire can be clamped and connected.

An electric conducting member 35 depends rigidly from the head 29 and in the present 55 instance I have illustrated this member in the form of a metallic tube which extends downwardly through the chamber 13 and the chamber 36 provided by the space within the mica tube 24; this tube 35 being of 60 smaller external diameter than the internal diameter of the mica tube 24 so that there is an air space entirely surrounding the metallic tube 35. The lower end of the metallic tube 35, when the cap 11 is screwed on the 65 body portion 9, is adapted to engage over the

top portion of the electrode wire 25 and make electric contact therewith. I prefer to slot the lower end of the tube 35 so as to make the same slightly resilient and capable of slightly yielding so as to pass over the 70 top of the electrode wire and then resiliently move into firm fitting engagement with the electrode wire. It will be noted that air is free to circulate through the perforations 14, chamber 13 and chamber 36 and in this manner the adjacent parts are kept cool during 75 use of the device. In addition to this, it will be noted that the air chamber 36 extends continuously from a position above the shoulder 15 to a position below the shoulder 80 85 15 and since this shoulder is the part employed for connecting the insulated electrode to the metallic shell (not illustrated) of the spark plug there is practically no possibility of transverse current leakage or short-circuiting. Thus with this construction I am enabled to increase to a very high degree the likelihood of maintaining the dielectric strength of the insulator and to eliminate electrical leakage through conduction at or 90 about the shoulder or thick portion of the insulator.

Furthermore by employing the structure as noted it is unnecessary to use objectionable cement, filled gaskets or the like and 95 yet a lasting sealed structure is provided.

While I prefer to employ two nuts on the electrode wire for engaging opposite surfaces of the web 21 of the insulator body, nevertheless if desired I may modify this 100 structure in slightly different forms as illustrated in Figures 4 to 7 inclusive.

In Figure 4, I have shown a structure wherein I retain the separate nut 28 but secure the lower nut directly to the electrode 105 wire as shown at 27^a or therefore this nut 27^a may be in the form of an integral part of the electrode wire.

In Figure 5, I have shown a reversal of the structure shown in Figure 4 wherein I 110 retain the separate nut 27 and make the nut 28^a a fixed part of the electrode wire and therefore this part 28^a may be an integral portion of the electrode wire.

In Figure 6, I have shown a structure in 115 which both of the nuts 28^b and 27^b are fixed to the electrode wire and therefore may be integral parts of said electrode wire. With this construction it would be necessary to apply a compression force to move the parts 120 28^b and 27^b into firm clamping position with the web 21 of the insulator.

In Figure 7, I have illustrated a form identical with that shown in Figure 2 with exception that I have illustrated washers or 125 gaskets 37 between the nuts and the web 21. It will be noted that the parts can be readily assembled and disassembled and if it is necessary at any time to replace the auxiliary mica tube, the same can be done by removing 130

the cap and the mica tube and then be pulled out of position and replaced by a new one.

While I have described my invention as taking a particular form, it will be understood that the various parts of my invention may be changed without departing from the spirit thereof, and hence I do not limit myself to the precise construction set forth, but consider that I am at liberty to make such changes and alterations as fairly come within the scope of the appended claims.

Having thus described my invention, what I claim as new and desire to secure by Letters Patent is:—

15 1. An insulated electrode including an insulating core providing a cavity and a web extending transversely of said cavity and including a hole; an electrode wire extending through said hole and into said cavity; 20 means on said wire for clamping engagement with opposite portions of said web whereby the electrode wire is positively secured to the insulating core, said insulating core including a cap detachably secured thereto; and an electric conducting member 25 secured to said cap and adapted to engage said electrode wire within said cavity, said conducting member having a tubular portion for fitting over said electrode wire; substantially as described.

2. An insulated electrode including an insulating core providing a cavity and a web extending transversely of said cavity and including a hole; an electrode wire extending through said hole and into said

cavity; means on said wire for clamping engagement with opposite portions of said web whereby the electrode wire is positively secured to the insulating core, said insulating core including a cap detachably secured thereto; and an electric conducting member secured to said cap and adapted to engage 40 said electrode wire within said cavity, said conducting member having a tubular portion for fitting over said electrode wire; substantially as described.

3. An insulated electrode including an insulating core body having a cavity extending downwardly therethrough; an auxiliary insulating tube fitting said cavity; an electrode having a portion extending upwardly into said cavity; a cap detachably secured 50 to said body and having a conducting portion secured thereto and adapted to extend into said cavity and engage said electrode, said body having a portion below said tube and through which said electrode extends; 55 and means on said electrode for clamping engagement with opposite sides of said latter portion; substantially as described.

In testimony whereof I have signed my name to this specification in the presence of 60 two subscribing witnesses.

WILLIAM S. THOMAS.
